UNITED STATES PATENT OFFICE.

JOHN B. CORNELL, OF NEW YORK, N. Y.

IMPROVED BURGLAR-PROOF SAFE.

Specification forming part of Letters Patent No. 22,547, dated January 11, 1859.

To all whom it may concern:

Be it known that I, JOHN B. CORNELL, of the city, county, and State of New York, have invented a new and useful Improvement in Burglar-Proof Safes; and I do hereby declare that the following is a full and exact description thereof, reference being had to the accompanying drawings, making a part of this specification.

Figure 1 is a front view of the open mouth of my improved safe; Fig. 2, a view of the upper end of said safe, and Figs. 3 and 4 are sections in the lines xx and yy of Fig. 1.

Similar letters indicate corresponding parts in each of the drawings.

My improvement in burglar-proof safes consists in combining a rabbeted cast-iron door-frame, $a b$, with the wrought-iron portions of the top, bottom, and sides of a safe in such a manner that the impenetrably hard molten iron which is afterward combined with the said wrought-iron portions of the safe (by any suitable molding and pouring operation) will also, by the same process, be so combined with the exterior surfaces of the said door-frame and with the bolt-sockets $m n$, which pass through the jambs of said frame, as to perfectly secure the said exterior surfaces of the door-frame against the approach of all burglarious cutting-instruments; while the exposed portions of said door-frame (before the door is placed therein) are sufficiently soft to be brought to the desired degree of finish by ordinary tools.

The wrought-iron portions of the top, bottom, back, and sides of my improved burglar-proof safe consist of the perforated double-casing plates $e f$, the exterior band, c , the inner angle-plates, $i i$, the outer angle-plates, $d d$, and the necessary rivets and screws to combine the said parts with each other and with the cast-iron door-frame $a b$, as represented in the drawings. The outer casing-plates, $f f$, after being combined with the angle-plates $d d$, are combined with the band c by means of the rivets $g g$, and the band c is combined with the door-frame by means of the screws $h h$. The inner casing-plates, $e e$, after being properly riveted to the angle-plates $i i$, are combined

with the door-frame by means of the screws $j j$. Sockets $m m$ may pass through the jamb b , on one side of the door-frame, into the recess within the same, for the reception of the lock-bolts, and nearly corresponding sockets $n n$ may be let into or cast with to opposite jamb of said door-frame for the reception of permanent projections on the inner edge of the safe-door. The apertures in the casing-plates $e f$ are of the outwardly-flaring shape represented in the drawings. It will therefore be perceived that when the molding sand is made to close the apertures of the casing-plates flush with the exposed surfaces of the same and the melted iron is poured into the space between said plates that it will also fill up the flaring apertures in the same, and as it hardens it will inseparably connect the said plates with each other. The said melted iron (which is represented by red ink cross-lines k in the drawings) will also flow into the space within the jambs of the door-frame and into the space between the rabbet of the door-frame and the band c , and as the said melted iron becomes chill-hardened in cooling the combination of metals which will then surround the door-frame of the safe will be of such a nature that they will resist every effort to break through the same and uncover the door or its fastenings that human ingenuity can by any possibility bring to its assistance in furtherance of such an object.

I do not intend to limit myself to any particular method of constructing the wrought-iron portions of a burglar-proof safe, nor to any particular method of combining the wrought portions of a safe with my cast-iron door-frame, provided the said parts of a safe be of such a shape, arrangement, and connection with each other that the hardening of the melted iron which is afterward combined with the prepared frame of said safe will afford the requisite and desired degree of protection to the outer lateral surfaces of its previously cast door-frame, substantially as herein set forth.

Having thus fully described my improvement in burglar-proof safes, what I claim

therein as my invention, and desire to secure by Letters Patent, is—

Combining a cast-iron door-frame with the wrought iron portions of the frame of a safe in such a manner that the molten iron, which is afterward, while in a melted state, combined with the said safe-frame, will form a burglar-proof protecting-casing around the

said door-frame, substantially as herein set forth.

The above specification of my improvement in burglar-proof safes signed and witnessed,

JOHN B. CORNELL.
